[57] CLAIM

The ornamental design for a folding chair, as shown and described.

DESCRIPTION

FIG. 1 is a perspective view of a folding chair in accordance with the present invention;

FIG. 2 is a right side elevational view of the folding chair of FIG. 1, with the left side elevational view being a mirror image thereof;

FIG. 3 is a top view of the folding chair of FIG. 1;
FIG. 4 is a front elevational view of the folding chair of FIG. 1;

FIG. 5 is a top plan view of the folding chair; and
FIG. 6 is a rear elevational view of the folding chair of FIG. 1.
